(57) **CLAIM**

The ornamental design for a cleaning and maintenance multi-tool for electronic devices, as shown and described.

DESCRIPTION

FIG. 1 is a perspective view of a cleaning and maintenance multi-tool for electronic devices showing my new design;

FIG. 2 is a top plan view thereof;

FIG. 3 is a side elevation view thereof;

FIG. 4 is another side elevation view thereof;

FIG. 5 is an exploded top plan view thereof showing the individual tool components separated from the multi-tool;

FIG. 6 is a top plan view thereof shown in an alternate configuration;

FIG. 7 is a top plan view of a single tool component shown isolated for clarity of disclosure;

FIG. 8 is a side elevational view of a single tool component shown isolated for clarity of disclosure; and,

FIG. 9 is sectional view taken along line 9-9 in FIG. 1.

Broken lines in FIGS. 5 and 6 illustrate environmental subject matter only and form no part of the claimed design.
